OSCILLATOR-MODULATOR CIRCUIT

Harold A. Wheeler, Great Neck, N. Y., assignor to
Hazeltine Corporation

Application January 20, 1932. Serial No. 587,681

17 Claims. (Cl. 250—20)

The present invention relates to oscillator modulators, and more particularly to an oscillator modulator for use in connection with super-heterodyne radio receivers.

5 In a superheterodyne radio receiver it is customary to convert the desired carrier or signal frequency currents into currents of a single predetermined intermediate frequency. The intermediate frequency is usually lower than the carrier frequency to facilitate the further amplification and selection of the desired signal. This frequency-changing process has, for the best results, formerly required an oscillator and modulator or first detector, each requiring an individual tube.

Although it has been proposed to utilize a single tube for the purpose of generating the local or heterodyne frequency currents, and combining the currents thus produced with the received signal currents, it has been found that a single tube could not perform both functions efficiently because of overloading effects of the oscillations, especially in the grid circuit, partly due to the widely differing oscillation voltages 25 obtained at the various portions of the tuning range of the oscillator. When a signal is applied from a tuned circuit to the grid of an oscillating vacuum tube, any appreciable grid current causes a damping of the tuned circuit and 30 a distortion of the signal currents, producing also cross modulation of the desired signal by strong interfering signals.

It is the principal object of the present invention to produce an oscillator modulator arrangement in which the oscillator shall be self-regulating to permit the grid circuit of the modulator to be free from overloading grid current at any point in the tuning range without a critical adjustment of the feed-back and without 40 relying upon overloading or saturation effects in the plate circuit to control the amplitude of oscillation.

It is a further object of the present invention to provide an oscillator modulator circuit in which the self-regulation of the oscillator may be employed without a sacrifice of conversion gain in the modulator.

These and further objects of this invention will become apparent from the following specification taken in connection with the accompanying drawing.

For accomplishing the objects of the present invention, there is provided an oscillator modulator circuit which employs an oscillator circuit 55 of the type shown in copending application for

"Feed-back circuits", Serial No. 540,581, filed May 28, 1931, of which this application is a continuation in part.

This oscillator circuit is of the uniform voltage type in which the feed-back from the output to the oscillation circuit includes a pair of couplings whose feed-back effects vary oppositely with frequency in order that the oscillation voltage may be maintained uniform as the tuning is varied. The feed-back from the oscillation circuit into the input circuit is so proportioned relative to the oscillation voltage that the maximum input voltage, due to the oscillation feed-back and the maximum signal input, will be insufficient to cause the grid to draw current and yet shall at all times be sufficient to maintain oscillations. The output circuit includes a portion of the oscillation circuit, providing a direct coupling to the output circuit which varies inversely with frequency in order to assist in promoting a uniform output for the oscillator modulator regardless of the frequency to which the oscillator is tuned.

Having thus briefly described this invention, attention is invited to the accompanying drawing, in which:

Fig. 1 is a diagram showing a simple oscillator, and

Fig. 2 is a modified circuit diagram showing an oscillator modulator embodying the features of the present invention.

Fig. 1, to which attention is now invited, includes a vacuum tube 11 of the tetrode or screen-grid type, which may be of type "224", and a resonant frequency-determining or oscillation circuit 22 including inductance 12, a fixed condenser 13, and a variable condenser 14 in series with each other. The junction between the condensers 13 and 14 is grounded, and the junction point between the condenser 13 and inductance 12 is connected to the anode of the tube 11 through an inductance 15 in series with fixed condenser 16. The cathode of tube 11 is connected to ground through an inductance 17 in series with a parallel combination of the radio-frequency by-pass condenser 18 and resistance 19, which serves the purpose of furnishing a bias voltage between the grounded grid and the cathode. The screen-grid is grounded through a battery 20. Inductances 17 and 15 are each magnetically coupled to inductance 12, as indicated by the brackets.

The anode potential for the tube is supplied by a battery 21 in series with choke coil 51. The radio-frequency component of the anode cur-

rent is conducted through the feed-back path including condenser 16, coil 15 coupled to coil 12, and condenser 13.

The operation of this circuit is as follows:

- 5 Coil 15 has a mutual inductance with coil 12 which is about half the self-inductance of the coil 12. At high frequencies this inductive coupling is the main feed-back from the plate circuit into the oscillation circuit 22. At low 10 frequencies the reactance of the condenser 13 has a value as high as one-third the reactance of the coil 12. Therefore, the total mutual reactance between the plate circuit and the oscillation circuit 22 varies between the limits of 15 50% and 83% of the reactance of the coil 12. The mutual inductance between the coils 12 and 15 is of such polarity that this coupling aids the coupling of the condenser 13. The mutual inductance between coils 17 and 12 is about one-fourth the self-inductance of coil 12. This ratio 20 does not vary with frequency, because only one kind of coupling, namely, inductive, is used in the cathode lead. The polarity of coil 17 is such that the alternating potential of the cathode 25 is intermediate between that of the grid (zero) and that of the plate. The coupling values of coils 15 and 17 and condenser 13 are proportioned so that at the lower frequencies the feed-back effect increases in the same manner as the dissipation in the oscillation circuit. The dissipation increases at the lower frequencies because the oscillating current squared increases at lower frequencies more rapidly than the resistance decreases.

30 The cooperation of the two kinds of feed-back yields a uniform oscillation voltage across coil 12 and also across coil 17.

35 When using the oscillator circuit in a superheterodyne, tuned input and output circuits are provided tuned to the carrier frequency and intermediate frequency, respectively. Such a circuit is shown in Fig. 2, to which attention is now invited. This circuit combines the functions of a beat oscillator and modulator. In this circuit a tuned circuit 3 is inserted in the grid lead of the tube 11. This circuit comprises the secondary inductance 4 of the input transformer, tuned by variable condenser 6. The inductance 4 is inductively coupled to the primary inductance 5, which may be the input or antenna inductance or the output of a radio-frequency amplifier stage. The circuit 3 is tuned to the carrier frequency.

40 The condenser 16 and the primary coil 51', which latter is the primary of an intermediate-frequency transformer, are so proportioned that the circuit including them is resonant to the super-audible beat or intermediate frequency, and the input 52 of an intermediate-frequency amplifier is coupled to the coil 51'.

45 In other particulars Fig. 2 is the same as Fig. 1, like parts being designated by the same reference characters.

50 It is to be noted that the output circuit includes the condensers 16 and 13, the latter of which constitutes part of the oscillation circuit 22. When the frequency of oscillations is low, the effective energy transferred between coils 12 and 17 becomes less, and therefore, under 55 normal circumstances, the output of the translation device would decrease. However, the impedance of the condenser 13 increases at low frequencies, resulting in a more nearly uniform 60 translation gain in the oscillator modulator.

Whereas the various circuit elements may have any of a large range of values, the following table gives characteristics which have been found to be suitable and which produce a circuit which will operate in accordance with the present invention:

Capacity of condenser 13	700 micro-microfarads	8
Capacity of variable condenser 14	0-350 micro-microfarads	85
Capacity of fixed condenser 16	200 micro-microfarads	90
Capacity of condenser 18	500 micro-microfarads	95
Inductance of each of coils 51 and 51'	5 millihenrys	90

95 Whereas the circuit of Fig. 2 has been described as part of a superheterodyne, the principles underlying the invention may be suitably employed for general use, such, for instance, as in heterodyne receivers or in transmitters adapted to be used on various wave-lengths. One form of transmitter to which this invention is especially applicable is that known as a tone-modulated continuous wave transmitter.

What is claimed is:

100 1. In a superheterodyne radio receiver, an oscillator-modulator circuit which includes a vacuum tube; an input circuit connected to the grid and cathode of said tube; an output circuit connected to the anode and cathode of said tube; a tunable circuit included in said input circuit 105 and tunable to the frequency of a signal; an oscillation circuit including in series a fixed condenser, a variable condenser, and an inductance; a connection between said inductance and said anode including a second fixed condenser; a 110 ground connection to said input circuit and to the junction of the two condensers of said oscillation circuit; an output inductance connected in said output circuit; a feed-back coupling between said oscillation circuit and the input circuit; 115 and a direct voltage source connected between said output inductance and ground; said fixed condensers being so proportioned that they serve to tune the output circuit to the intermediate frequency produced by the modulation 120 of the signal by the oscillations produced by said oscillation circuit.

125 2. In a superheterodyne radio receiver, an oscillator modulator circuit which includes a vacuum tube; an input circuit connected to the grid and cathode of said tube; an output circuit connected to the anode and cathode of said tube; a tunable circuit included in said input circuit 130 and tunable to the frequency of a signal; an oscillation circuit including in series a fixed condenser, a variable condenser, and an inductance; a connection between said inductance and said anode, said connection including a second fixed condenser; an output inductance connected in 135 said output circuit; a feed-back coupling between said oscillation circuit and the input circuit; said condensers being so proportioned that they will serve to tune the output circuit to the intermediate frequency produced by the modulation 140 of the signal by the oscillations produced by said oscillation circuit.

145 3. In a superheterodyne radio receiver, an oscillator modulator circuit which includes a vacuum tube having anode, grid, and cathode; an input circuit connected to said grid and said cathode; a tunable circuit including in said input circuit and tunable to the frequency of a signal; an oscillation circuit including in series a fixed condenser, a variable condenser, and an inductance; 150

tance; a feed-back coupling between said oscillation circuit and the input circuit of the tube; a connection between said inductance and said anode; and an output circuit connected between said anode and said cathode and including an output inductance, said connection, said fixed condenser, and a source of high potential energy connected between said output inductance and the junction of the two condensers of said oscillation circuit, whereby the fixed condenser of said oscillation circuit is also included in the output circuit and thus simultaneously serves to assist in tuning the output circuit to resonance with the desired frequency and in producing a capacitive coupling between the output circuit and the oscillation circuit, which coupling will vary inversely with frequency.

4. In a superheterodyne radio receiver, an oscillator modulator circuit which includes a vacuum tube having input and output terminals; an input circuit connected to said input terminals and including a resonant portion which is tunable to the frequency of a signal; a tuned oscillation circuit inductively coupled to said input circuit and tunable to the oscillation frequency; a tuned output circuit connected to the output terminals of said vacuum tube and coupled to said oscillation circuit, said circuit being tuned to the intermediate frequency; an intermediate-frequency circuit inductively coupled to said output circuit; and a capacitive coupling common to said oscillation circuit and said output circuit, whereby the reactance of said oscillation circuit upon said output circuit will increase with a decrease in frequency to offset decrease in transfer voltages due to the inductive coupling between the oscillation circuit and input circuit.

5. In a superheterodyne radio receiver, an oscillator modulator system which includes a vacuum tube having input and output electrodes, input and output circuits connected to said input and output electrodes, respectively, an oscillation circuit coupled between said input and output circuits, means for tuning said output circuit to the intermediate frequency, an intermediate-frequency amplifier input circuit inductively coupled to said output circuit, and reactance means, common to said oscillation and output circuits, said reactance means being of such a character that the reactance of said oscillation circuit upon the input circuit will increase with a decrease in frequency to permit a uniform translation gain in said oscillator modulator.

6. In a superheterodyne radio receiver, an oscillator modulator circuit which includes a vacuum tube having anode, grid, and cathode; an input circuit connected between said cathode and said grid and including a portion which is tunable to the frequency of a signal; an oscillation circuit including a fixed condenser, a variable condenser, and an inductance in series; a connection between said inductance and said anode including a third condenser; an output inductance connected to said anode; a connection from said inductance to a junction of the two condensers of said oscillation circuit, whereby said output inductance is tuned by the fixed condenser of said oscillation circuit and the third-mentioned condenser, and whereby the capacitive coupling between said oscillation and output circuits will tend to give a uniform translation gain to said oscillator modulator circuit.

7. An electric generating system which in-

cludes a vacuum tube having input and output terminals, a circuit connected to the input terminals of said tube and including a tunable resonant portion, a fixed resonant circuit connected to the output terminals of said tube, a tunable oscillation circuit coupled to said input and said output circuits, and a fixed auxiliary impedance means coupled thereto and to said fixed resonant circuit, whereby substantially uniform output voltage is developed by said generator.

8. An electric generating system which includes a vacuum tube having input and output terminals, input and output circuits connected to said input and output terminals, respectively, said input circuit including a portion which is tunable to a first frequency and said output circuit being tuned to a second frequency, a tunable oscillation circuit tuned to a third frequency and inductively coupled to the input and coupled to the output circuits of said tube, and a fixed impedance common to said output circuit and said oscillation circuit, whereby the effective coupling between said oscillation circuit and said output circuit increases with a decrease in frequency to offset the changes caused by the inductive feed-back coupling as said oscillation circuit is tuned through a band of frequencies.

9. An oscillator modulator circuit comprising a vacuum tube having grid, cathode, and anode; an oscillation circuit including in series an inductance, a fixed capacity and a variable capacity connected; a fixed coupling capacity connected between said inductance and said anode; a ground connection connected to the junction of the capacities of said oscillation circuit; an output inductance connected to said anode; and a source of high potential energy connected between said output inductance and ground whereby the fixed capacity of said oscillation circuit and the coupling capacity between said circuit and the anode of said tube serve to tune said inductance to the output frequency of said oscillator.

10. An electric generating system which includes a vacuum tube having input and output terminals, input and output circuits connected to said input and output terminals, respectively, said input circuit including a portion which is tunable to a first frequency and said output circuit being tuned to a second frequency, a tunable oscillation circuit tuned to a third frequency and coupled to the output and input circuits of said tube, and a fixed impedance common to said output circuit and said oscillation circuit, whereby the reactance of said circuit upon the output circuit will increase with a decrease in the frequency to which said oscillation circuit is tuned.

11. An oscillator system, tunable over a frequency range, comprising a vacuum tube having cathode, grid, and anode; an oscillation circuit including an inductance; a fixed condenser and a condenser which is variable to tune said circuit; a condenser connected between said inductance and said anode; and an output inductance connected to said anode and tuned by means of said last-mentioned condenser and the fixed condenser of said oscillation circuit.

12. An electric generating system which includes a vacuum tube having input and output terminals, input and output circuits connected to said input and output terminals, respectively, a tunable oscillation circuit coupled to both of said circuits, a utilization circuit inductively coupled to said output circuit, the coupling be-

5 between said oscillation circuit and said input circuit being inductive, and the coupling between said output circuit and said oscillation circuit being combined capacitive and inductive, where-
5 by the reactance of said oscillation circuit upon
10 said output circuit will increase with a decrease in frequency to offset the decrease in transfer voltage caused by the inductive coupling be-
15 tween the oscillation circuit and the input cir-
cuit.

13. An electric generating system which in-
15 cludes a vacuum tube having input and output terminals, input and output circuits connected to said input and output terminals, respectively, a tunable oscillation circuit coupled to both of said circuits, a utilization circuit inductively coupled to said output circuit, the coupling be-
20 tween said oscillation circuit and said input circuit being inductive, and the coupling between
25 said output circuit and said oscillation circuit being capacitively reactive, whereby the reactance of said oscillation circuit upon said output circuit will increase with a decrease in frequency to offset the decrease in transfer voltage caused by the inductive coupling between the oscillation circuit and the input circuit.

14. An electric generating system which in-
30 cludes a vacuum tube having input and output terminals, an input circuit connected to the input terminals of said tube, an output circuit connected to the output terminals of said tube, a tunable oscillation circuit coupled to said input and output circuits, and a fixed auxiliary im-
35 pedance means coupled thereto and to said output circuit, whereby substantially uniform output voltage is developed by said generator.

15. An oscillator modulator circuit comprising a vacuum tube having grid, cathode, and anode; an oscillation circuit including in series

an inductance, a fixed capacity, and a variable capacity; a coupling capacity connected between said inductance and said anode; an output inductance connected to said anode; and a source of high potential energy connected between said output inductance and the junction of the capacities of said oscillation circuit, whereby the fixed capacity of said oscillation circuit and the coupling capacity between said circuit and the anode of said tube serve to tune said inductance to the output frequency of said oscillator. 80 85

16. An electric generating system which in-
cludes a vacuum tube having input and output terminals, input and output circuits connected to said input and output terminals, respectively, a tunable oscillation circuit coupled to the output circuit of said tube and coupled to the input circuit thereof, and a fixed impedance com-
mon to said output circuit and said oscillation circuit, whereby the reactance of said circuit upon the output circuit will increase with a de-
crease in the frequency to which said oscillation circuit is tuned. 90 95

17. An electric generating system which in-
cludes a vacuum tube having input and output 100 terminals, input and output circuits connected to said input and output terminals, respectively, a tunable oscillation circuit tunable to a desired oscillation frequency and coupled to the input and output circuits of said tube, and a fixed im-
pedance common to said output circuit and said oscillation circuit, whereby the effective coupling between said oscillation circuit and said output circuit increases with a decrease in frequency to offset the changes caused by the inductive 110 feed-back and output couplings as the said oscillator circuit is tuned through a band of frequencies. 105 110
